UNITED STATES PATENT OFFICE.

DANIEL W. TOWER, OF GRAND RAPIDS, MICHIGAN.

DRAWER-PULL.

SPECIFICATION forming part of Letters Patent No. 634,778, dated October 10, 1899.

Application filed July 12, 1899. Serial No. 723,613. (No model.)

To all whom it may concern:

Be it known that I, DANIEL W. TOWER, a citizen of the United States, residing at Grand Rapids, in the county of Kent and State of Michigan, have invented new and useful Improvements in Drawer-Pulls, of which the following is a specification.

This invention relates to a new and novel drawer-pull; and the invention consists in the construction and combination of parts hereinafter pointed out.

The objects of my invention are, first, to furnish a cheap, tasty, and convenient drawer-pull to be applied to drawers of chiffonniers, dressing-cases, and other similar articles of furniture, and, second, to form a drawer-pull in which the joint attaching the pull to the front of the drawer is sunk in the drawer and does not project therefrom, but still constructed

20 in such a shape or form as to allow the pull itself to be raised and lowered in the ordinary manner. These objects I accomplish by means of the mechanism illustrated in the accompanying drawings, in which—

25 Figure 1 shows the front elevation of a drawer provided with a pull attached thereto constructed in accordance with my invention. Fig. 2 shows a sectional view on line X X of Fig. 1, showing the socket which receives the

30 ball which is attached to the handle or pull. Fig. 3 shows a sectional view similar to the one shown in Fig. 2, but applied to a curve or "swell" front, as the same is sometimes called.

Fig. 4 shows a detail of the pull and the ball 35 secured thereto, forming, in connection with the socket, the joint for the drawer-pull. Fig. 5 shows the front elevation of a drawer having a modified form of pull. Fig. 6 shows a cross-section through the center of the socket

40 when the socket and attachment are constructed in accordance with the modified form shown in Fig. 5. Fig. 7 shows a section of the modified form of socket, and Fig. 8 shows a front view of this modified form of socket.

45 Similar letters refer to similar parts throughout the several views.

A represents the ball, which in the form of my invention shown in Figs. 1, 2, 3, and 4 is secured to the handle by means of a pivot, 50 hereinafter described.

B shows the bail or handle.

C shows the socket, the ball A fitting into the socket, as shown in Figs. 1, 2, and 3.

D is a screw, sometimes provided with a head or washer, which is used for attaching 55 the socket to the drawer-front.

E shows a pin which passes through both the ball A and the socket C. This pin or pivot passes through a tapered opening, (shown by F, the object of this taper being to allow 60 the ball and handle to adjust itself and adapt the same to be used both on straight fronts, as shown by Fig. 2, and on the curved or swell fronts, as shown by Fig. 3. In Fig. 3 I have shown the front swell or curve by I. 65

K (represented by dotted lines in Fig. 4,) shows the hole for the reception of the end of the bail B. In this form of my invention the bail B passes through this hole K and receives the pivot which fits into the taper opening F, 70 as above described.

In Fig. 6, B' shows the position of the bail B when raised. C' shows the modified form of socket. In this form of socket no pivot-pin is used, the ball being held in position by 75 means of the socket itself, which socket is provided with a slot allowing the bail to be moved or swung from a horizontal to substantially a perpendicular position. This socket is provided with a slotted cap G, the 80 slot in the cap G being shown in Figs. 5, 6, 7, and 8 by H.

When the hinge is constructed as described in the modified form, the ball A is slipped upon the end of the bail and secured 85 thereto in any suitable manner.

While this construction is in a certain sense a ball-and-socket joint, yet the movement of the bail is limited by the slot, so that it always swings in the same plane. 90

Having thus described my invention, what I claim to have invented, and desire to secure by Letters Patent, is—

1. In a hinge for a drawer-pull, the combination with a drawer-front of a socket sunk 95 therein, a handle or pull provided with a ball fitting into said socket, the movement of the handle or pull being limited by the form of the socket, substantially as described.

2. In combination with a socket set into 100 the front of the drawer, a ball secured to the drawer-pull, fitted into the said socket, said

socket being provided with a cap and a slot, said cap adapted to retain the ball in position, and the slot adapted to allow the pull to be raised and lowered for use, substantially 5 as described.

3. The combination with a drawer-front of a socket sunk therein, a ball provided with a double tapering hole, as shown, a handle or pull secured to the ball, and a pivot passing through the ball securing the same in po- 10

sition with the socket, substantially as described.

In testimony whereof I have hereunto set my hand in presence of two subscribing witnesses.

DANIEL W. TOWER.
